FASTENING INSERTING MACHINE

Charles A. Robinson, Salem, Mass., assignor to
United Shoe Machinery Corporation, Flemington, N. J., a corporation of New Jersey

Original application December 20, 1944, Serial No. 568,964. Divided and this application August 3, 1945, Serial No. 608,704

25 Claims. (Cl. 1—20)

1

This invention relates to fastening-inserting machines, the present application being a division of a copending application for Letters Patent for improvements in Machines for use in the manufacture of shoes, Serial No. 568,964, filed on December 20, 1944. The machine shown in that copending application is a toe-lasting machine having wipers which wipe the margin of the toe end of a welt shoe upper into lasted position against a lip on the insole in the course of a cycle of power operations of the machine resulting from actuation of a clutch, means for applying a wire binder about the toe against the margin of the upper also in the course of the cycle of operations, and fastening-inserting mechanisms which during a pause in the cycle fasten the binder at the opposite sides of the shoe respectively by inserting fastenings in the margin of the upper and the lip of the insole in directions widthwise of the lip. The present invention relates more particularly to the fastening-inserting mechanisms certain novel features of which are applicable to other uses than the fastening of binders.

As applied to mechanism for inserting a fastening in the margin of an upper and the lip of an insole in a direction widthwise of the lip the invention, in one aspect, provides a novel construction such that prior to the insertion of the fastening the fastening-inserting mechanism is moved heightwise of the shoe to a position determined by the shoe. As herein illustrated, the mechanism comprises a throat member for guiding the fastening, a driver for driving it and an anvil for clinching the fastening on the inner side of the lip, these parts being movable as a unit to positions determined by engagement of the anvil with the insole, after which the throat member and the anvil are moved toward each other to clamp the margin of the upper and the lip between them prior to the driving of the fastening. The construction shown is further such that the fastening utilized is a staple which, after the positioning movement of the mechanism heightwise of the shoe, is formed by means operative in response to resistance of the shoe to further movement of the mechanism.

In accordance with another feature the invention provides, in staple-forming and driving mechanism, novel means whereby wire for use to form a staple is fed by movement of the mechanism to position it relatively to the work. In the illustrated embodiment of the invention the means for imparting the above-mentioned positioning movement heightwise of the shoe to

the mechanism first moves a cutter into contact with the wire so that through such contact the wire is fed by the movement of the mechanism, after which the wire is cut and the staple is formed when the shoe prevents further such movement. After the driving of the staple the mechanism is moved reversely along the wire and thus receives a length of wire for use in forming the next staple, such reverse movement of the mechanism being limited by engagement with the end of the wire which is so controlled as to serve effectively as the limiting means.

The invention further provides novel means for limiting the operative movement of the driver in accordance with the position of the throat member when in contact with the work. As illustrated, the throat member and the driver are operated respectively by different toggles, the toggle for operating the throat member having a further definitely limited movement after engagement of the throat member with the work, and such further movement of that toggle serves to adjust the driver-operating toggle to cause the driver at the end of its operative movement to be positioned in a definite predetermined relation to the throat member. In this manner insurance is afforded that the fastening will be driven precisely the desired distance into the work.

30 The above and other features of the invention, including various novel details of construction and combinations of parts, will now be more particularly described with reference to the accompanying drawings and thereafter pointed out in the claims.

In the drawings,

Fig. 1 is a view in front elevation of the upper portion of the machine to which the invention is herein shown as applied;

40 Fig. 2 is a view mainly in front elevation, on a larger scale, showing one of the fastening-inserting mechanisms;

Fig. 3 is a section on the line III—III of Fig. 2;

Fig. 4 is a section on the line IV—IV of Fig. 2;

45 Fig. 5 is a section on the line V—V of Fig. 2;

Fig. 6 is a section on the line VI—VI of Fig. 2;

Fig. 7 is a section on the line VII—VII of Fig. 2;

Fig. 8 is an exploded view, in perspective, of portions of the fastening-inserting mechanism shown in Figs. 2 and 7;

50 Fig. 9 is a view partly in front elevation and partly in section, showing the mechanism in position to drive a staple after the staple has been formed;

Fig. 10 is a view in side elevation of a device for controlling the staple wire;

Fig. 11 is a view similar to Fig. 9, but with parts broken away, showing portions of the mechanism as they appear at the end of the staple-driving operation; and

Fig. 12 is mainly a plan view, with parts removed and a portion of the shoe broken away to show the staple when the parts are positioned as in Fig. 11.

In view of the disclosure in the above-mentioned copending application of which this application is a division, the present description will be confined to such portions of the machine as it is necessary to refer to for an understanding of the invention. The welt shoe is positioned for the toe-lasting operation by a device 2 constructed substantially as disclosed in Letters Patent No. 2,388,367, granted November 6, 1945, on an application of mine, this device being arranged to engage the bottom face of the toe end of the insole adjacent to its lip *a* (Fig. 12) to position the shoe heightwise and also to engage the inner face of the lip at the end and the sides of the toe to position it lengthwise and laterally. The shoe is thus positioned when it is presented to the machine by the operator, and shortly after the starting of the cycle of power operations of the machine by actuation of a clutch (not shown) it is clamped against the device 2 by a toe rest 4 which is moved upwardly into clamping position. To assist in controlling the shoe there is also provided a heel rest 6 (Fig. 1) which is moved rearwardly into engagement with its heel-end face early in the cycle. In the course of the cycle of operations also a pair of wipers 8 (Figs. 1 and 12) are advanced and closed to embrace the upper about the toe end of the last and are moved upwardly to wipe the upper heightwise of the last, after which they are further advanced and closed to wipe the marginal portion of the upper inwardly over the feather and against the lip of the insole, the lip being supported against the inward pressure of the wipers by the device 2. In predetermined time relation to the operation of the wipers a wire binder *w* is applied about the toe end of the upper to hold it in lasted position by means of a pair of grippers 10, one of which is shown in Fig. 12, the grippers pulling the binder inwardly under the wipers and against the upstanding margin of the upper opposite the lip of the insole. The binder having thus been applied and its opposite end portions having been positioned by the grippers in the angle between the feather and the lip of the insole beyond the ends of the wipers, the cycle of operations of the machine is automatically interrupted to permit the binder to be fastened to the shoe during a pause in the cycle.

For thus fastening the binder the machine is provided with a pair of fastening-inserting mechanisms which may be termed stapling units, these units being operated to form staples and to drive them over the binder and through the upstanding margin of the upper and the lip of the insole in locations beyond the ends of the wipers while the binder is held against the margin of the upper by the wipers. The two units are positioned at the front of the machine and are identical except for such differences as are necessitated by the fact that they operate respectively at the opposite sides of the shoe. Each unit includes a main bar 12 arranged to extend generally widthwise of the shoe and provided near its outer end with a guideway 14 (Figs. 6 and 7)

in which is mounted a crosshead 16 formed on one end of a shaft 18 which is mounted to turn in a bearing 20 secured to one side of the frame of the machine. The bar 12 and the parts thereon may thus swing in directions heightwise of the shoe about the axis of the shaft 18 and may move relatively to the shaft in directions widthwise of the shoe. Slidably mounted on the top of the bar 12 is a plate 22 which is confined on the bar by two screws 24 extending through slots 26 (Fig. 2) in the plate. Near its outer end the plate 22 has a downwardly extending arm 28 (Fig. 7) arranged to engage the bearing 20 and to be engaged on its outer side by the end of a screw 30 threaded in a member 32 which is secured to the lower face of the bar 12. Connected to the outer end of the bar and to the frame of the machine is a spring 34 which tends to move the bar lengthwise in an inward direction, its inward movement being adjustably limited by engagement of the screw 30 with the arm 28 of the plate 22. It will be understood that since the arm 28 is in engagement with the bearing 20 and since the plate 22 is slidably mounted on the bar 12, turning of the screw 30 serves to adjust the bar relatively to the plate in directions widthwise of the shoe as may be required by shoes of different widths.

Slidably mounted in a guideway 36 (Fig. 8) in the inner end portion of the bar 12 is a staple-guiding throat or nozzle 38 which includes a small block 40 and another member 42 secured to the block and extending outwardly along the bar 12 beyond the block. Secured to the member 42 in spaced relation to the block 40 is a member 44 which serves as an outside former and by moving inwardly toward the shoe with the throat 38 forms a staple over an inside former 46 extending through a slot 48 (Fig. 7) in the member 42. An enlarged portion of the inside former is slidably mounted in an opening in one side of the bar 12 and in a cap member 50 secured to the side of the bar and extends into a slot 52 formed in one side of the member 42. A spring 54 presses the inside former inwardly as far as permitted by its engagement with the member 42. Mounted in the space between the block 40 and the outside former 44 is a small block 56 which is positioned opposite the inside former (Figs. 2 and 4) when the parts are in their initial positions and is provided with a slot into which the staple-forming portion of the inside former extends. A pair of springs 58 positioned between the block 56 and the member 42 tend to move the block in a direction away from the inside former and hold it initially in a slot 60 (Fig. 7) formed in a small plate 62 which by means of two screws 64 (Fig. 2) is secured to one side of the bar 12. With the block in this position a space is provided between it and the member 42 for the wire from which the staple is to be formed and for the bending of the legs of the staple about the inside former. In a manner hereinafter described the wire is fed into this space, between the outside former and one edge of the inside former, through a nipple 66 which is mounted in an opening in the bar 12. The length of wire required for the staple is severed from the rest of the wire, in response to movement of the throat 38 and the outside former inwardly toward the shoe, by a cutter 68 which is fastened to the top of the outside former 44 and has a cutting edge substantially contiguous to the lower end of the nipple 66 when the parts are in starting positions. In response to the

movement of the throat and the outside former, as soon as the staple is formed, the inside former is forced outwardly by engagement of the member 42 therewith at one end of the slot 52 in this member to provide a clear path for a staple driven 70 which moves in guideways formed in the members 40 and 44. Also in response to the same movement the block 56 is forced inwardly against the resistance of the springs 58 by engagement of the plate 62 therewith at one end of the slot 60 in the plate to close the space between the block and the member 42 and thus to assist in guiding the formed staple, the block being provided with a staple guideway arranged to align with the guideways in the members 40 and 44.

Operative movement is imparted to the throat 38 and the outside former 44 through a toggle comprising a pair of links 72 and 74 which are connected together by a stud 76, the link 72 being connected to the throat and the outside former by a pin 78 carried by the members 42 and 44. As shown in Fig. 7, this pin has an opening through it for the passage of the driver 70. The link 74 is connected at its outer end to a stud 80 mounted in a block 82 which is slidably movable along a guideway in the bar 12 and is controlled by a spring 84 mounted in a cap 86 secured on the outer end of the bar. This spring normally holds the block 82 in a position determined by its engagement with a shoulder 88 (Fig. 7) on the bar 12. The link 74 is mounted on an eccentric portion of the stud 80, and the stud may be turned in the block 82 for a purpose hereinafter explained. It is held in adjusted position by a nut 90 threaded on the portion thereof which extends through the block. The toggle 72, 74 is operated by fluid-pressure means comprising a piston 92 vertically movable in a cylinder 94 fast on the front of the frame (Fig. 1). The piston is connected to a projection on the toggle link 72 at the knee of the toggle by a link 96 which is mounted at its upper end on a stud 98 (Fig. 3) in the piston and extends through a slot in the lower end portion of the piston. When fluid is admitted to the upper end of the cylinder 94 the piston 92 is moved downwardly against the resistance of a spring 100 connected to its lower end and starts to straighten the toggle 72, 74, thereby imparting inward movement to the throat 38 and the outside former 44. Almost immediately, however, the cutter 68 carried by the outside former engages the wire extending downwardly from the nipple 66, and the resistance of the wire prevents further straightening of the toggle. Continued movement of the piston, therefore, causes the bar 12 and the parts thereon to swing downwardly about the axis of the shaft 18, and in this manner a staple-clinching anvil 102 fast on the inner end of the bar is carried downwardly into engagement with the insole. The bar 12 is initially so adjusted by the screw 30 that when the anvil thus engages the insole it is positioned farther inwardly over the insole than the lip a. By reason of the resistance of the shoe to further downward swinging movement of the bar the toggle is then further straightened to cause the cutter 68 to cut the wire and to cause the outside former 44 to move inwardly and form a staple over the inside former 46. At the same time the throat 38 is moved inwardly toward the shoe until it engages the upper in the angle between the feather and the lip of the insole, as illustrated in Fig. 9, the end of the throat having therein a groove 104 (Fig. 8) in

which the binder w is located when the throat is at the limit of its inward movement.

As the throat and the outside former are thus moved inwardly the bar 12 is moved in an outward direction against the resistance of the spring 34 to bring the anvil 102 against the inner face of the lip of the insole as shown in Fig. 9. For this purpose there is pivotally mounted on a member 106 (Fig. 2) fast on the frame a lever 108 the lower end of which is arranged to engage an upwardly extending arm 110 formed on the inner end of the plate 22. The upper end of the lever is connected by a link 112 to a pin 114 (Fig. 3) in the piston 92. The connection between the link and the lever comprises a pin 116 carried by the lever and extending through a slot 118 in the link, the pin being engaged by a spring 120 in the link. Accordingly the link acts on the lever to move the bar 12 in an outward direction, as above described, through the plate 22 the arm 28 of which is in engagement with the screw 30 on the bar, and after the anvil 102 engages the inner face of the lip of the insole the spring 120 yields to permit the link 112 to move relatively to the lever during further downward movement of the piston 92. As shown in Fig. 2, the lower end of the lever 108 is spaced initially from the plate 22 and its arm 110 to prevent the outward movement of the bar 12 until after the anvil 102 has substantially completed its downward movement. After the upstanding margin of the upper and the lip of the insole have been clamped between the throat 38 and the anvil 102, further straightening of the toggle 72, 74 serves to move the block 82 (Figs. 2 and 5) outwardly against the resistance of the spring 84. To limit the straightening of the toggle there is fast on the bar 12 a stop member 122 arranged to engage the toggle link 74, as shown in Fig. 9.

To insure that the portion of the binder adjacent to the throat 38 will be located in proper relation to the staple guideway in the throat, there is provided a finger 124 the inner end of which engages the binder underneath and lifts it to the proper height. This finger is pivotally supported at its outer end on the pin 78 through which the throat and the outside former are operated, and it is controlled by a pin 126 projecting from the throat member 40 in a manner which need not be herein further described but is fully disclosed in the copending application Serial No. 568,964.

The staple driver 70 is fastened to a driver bar 128 which is movable along the previously mentioned guideway 14 in the bar 12. The driver is operated through a second toggle comprising a pair of links 130 and 132 connected together by a stud 134, the link 130 being connected to the driver bar 128 by a stud 136 which extends through a slot 138 (Figs. 7 and 8) in the bar 12. The link 132 is connected to the previously mentioned slidable block 82 by a stud 140. The toggle 130, 132 is operated by fluid-pressure means comprising a piston 142 (Fig. 1) movable in a cylinder 144 which is integral with the previously mentioned cylinder 94, the piston being connected by a link 146 to a projection on the toggle link 130 at the knee of the toggle. The piston is moved downwardly against the resistance of a spring 148 connected to its lower end. The fluid for operating the piston 142 is admitted to the cylinder 144 from the cylinder 94 through a port 150 when the piston 92 is moved downwardly from its starting position far enough to uncover this

port. The piston 142 also extends upwardly initially beyond the port 150, and it is pulled downwardly against the resistance of the spring 148 to uncover the port by the previously described downward swinging movement of the bar 12, the bar acting on the piston through the toggle link 130 since the pin 136 connecting this link to the driver bar 128 is at that time at the outer end of the slot 138 (Fig. 7). It will be understood that by reason of the resistance of the spring 148 to the downward swinging movement of the bar 12 insurance is afforded that the cutter 68 will be forced against the wire as hereinbefore described through the toggle 72, 74 before the bar starts to swing downwardly. After communication is established between the cylinders 94 and 144 through the port 150 it is still necessary to prevent the driver from operating until the toggle 72, 74 has been substantially straightened to complete the forming of the staple and the inward movement of the throat 38. Temporarily, therefore, the straightening of the toggle 130, 132 is prevented even after the fluid is admitted to the cylinder 144. For this purpose there is pivotally mounted on a stud 152 on the bar 12 a stop member 154 one end of which is arranged to lie in the path of movement of the stud 136 and to engage that portion of the link 130 which is mounted on the stud. A spring 156 mounted in a holder 158 which is fastened on a small cover plate 160 on the front of the bar 12 engages a tail 162 on the stop member 154 to hold the member in that position. When the toggle link 72 nears the limit of its movement, a small block 164 carried by the link engages the stop member 154 and swings it downwardly against the resistance of the spring 156 out of the path of movement of the stud 136 and the link 130 (Fig. 9). This serves to release the driver-operating toggle to cause the driver to be operated by the fluid in the cylinder 144. The movement of the driver-operating toggle is limited by engagement of its link 130 with the stop member 122, as shown in Fig. 11.

Reference has been made to the fact that after the upstanding margin of the upper and the lip of the insole have been clamped between the throat 38 and the anvil 102, any further straightening of the throat-operating toggle, until its movement is stopped by the member 122, serves to move the block 82 outwardly along its guideway against the resistance of the spring 84. This block, therefore, assumes a position depending upon the position assumed by the throat in accordance with the thickness of the shoe materials between the throat and the anvil, and since the link 132 of the driver-operating toggle also is connected to the block 82, this toggle is adjusted by the throat-operating toggle to determine the limit of the operative movement of the driver 70 in accordance with the position of the throat. The staple-engaging end of the driver will, therefore, be located in a definitely predetermined relation to the throat 38 when the driver is at the end of its staple-driving movement. In the illustrated embodiment of the invention insurance is thus afforded that the driver will not drive the staple too far with a possible tendency to cut the wire binder. By adjustment of the eccentric stud 80 the relation between the throat and the driver when these parts are at the limits of their operative movements may be varied to vary the distance that the staple is driven into the work. The anvil 102 has therein a clinching cavity 166 (Fig. 7) so arranged relatively to the driver as to deflect the staple legs in directions toward the

heel end of the shoe and outwardly into the lip of the insole, as illustrated in Fig. 12.

The wire W from which the staples are formed by the two stapling units is supplied from a pair of reels 168 (Fig. 1) rotatably mounted on brackets 170 which are secured to the front of the frame and passes over idler pulleys 172, portions only of which are shown, and thence downwardly to the respective units. Each strand of wire extends downwardly through a guide 174 fast on the front of the frame, and pivotally mounted on this guide is a bell-crank lever 176 (Fig. 10) one arm of which is arranged to engage the wire and to serve as a brake to prevent reverse upward movement of the wire while permitting it to be moved freely downward. A spring 178 acts on the other arm of the bell-crank lever to hold the first-mentioned arm in frictional engagement with the wire. Below the brake the wire extends through a flexible tube 180 which may be a coil spring and the lower end of which extends into the previously mentioned nipple 66 and is held herein by a screw 182 (Fig. 4). The upper end portion of the flexible tube is mounted to slide freely in upward and downward directions in a guide 184 fast on the frame. As already explained, the first action of the toggle 72, 74 in response to the admission of fluid to the cylinder 94 is to move the knife 68 into engagement with the wire adjacent to the lower end of the nipple 66, after which the bar 12 is swung downwardly to carry the anvil 102 into engagement with the insole before the wire is cut by further straightening of the toggle. This downward swinging movement of the bar, by reason of the engagement of the knife with the wire, serves to feed the wire for use in forming the staple to be driven in the next shoe. It will be understood that after the fastening of the binder each stapling unit is swung upwardly by the springs 100 and 148 upon release of the fluid from the cylinders 94 and 144, and since the wire is prevented from moving upwardly by the brake 176, the upward movement of the unit causes the wire to enter the space between the outside former 44 and the inside former 46 until its lower end engages the lower wall of the guideway 36 (Fig. 8) in the bar 12. In this operation the flexible tube 180 slides upwardly in the guide 184. The end of the staple wire thus serves as a stop to limit the upward swinging movement of the stapling unit, and insurance is thereby afforded that the proper amount of wire to form the staple is fed to the unit. It will be evident, however, that the wire cannot enter the space between the inside former and the outside former until after the staple driver and the outside former have been retracted by their operating toggles upon release of the fluid from the cylinders 94 and 144. The engagement of the end of the wire with the top of the knife 68 prevents the upward swinging movement of the unit until the driver and the outside former have been thus retracted.

Leading to the upper ends of the cylinders 94 and 144 respectively are conduits 186 and 188 for operating fluid, preferably oil, under pressure. These conduits are controlled by automatic valve mechanism (not herein shown) whereby the operations of the stapling units are initiated immediately prior to the previously mentioned pause in the cycle of operations of the machine and whereby the fluid is released from the cylinders after the driving of the staples to cause the units to return to their starting positions, as fully disclosed in the copending application Serial

No. 568,964. In each conduit 188 is a check valve 190 which is normally closed to prevent the piston 142 from being operated by any fluid except that delivered from the cylinder 94 through the port 150 when this port is uncovered. The purpose of the check valve is to expedite the exhaust of the fluid from the cylinder 144 and to permit the exhaust of fluid in the upper end of the cylinder beyond the port 150 in the return of the parts to starting positions.

The manner of operation of the machine, in so far as it is of interest with reference to the present invention, will now be briefly summarized, a complete disclosure of its operation as a whole being furnished in application Serial No. 568,964.

The operator presents the shoe in the position determined by engagement of the shoe-positioning device 2 with the toe end of the insole, and then starts the cycle by actuation of the clutch, whereupon the toe rest 4 and the heel rest 6 are moved to their shoe-supporting positions. In the course of the lasting of the toe end of the shoe which then takes place the wipers 8 wipe the marginal portion of the upper inwardly over the feather and against the lip of the insole, and a wire binder *w* (Fig. 12) is applied about the toe in upper-holding position, the binder being pulled inwardly under the wipers and against the up-standing margin of the upper by a pair of grippers 10, one at each side of the shoe. The binder having thus been applied and being pressed against the upper by the wipers, the cycle of operations is automatically interrupted to permit the binder to be fastened to the shoe forwardly of the ends of the wipers during a pause in the cycle. Just prior to the pause in the cycle the operating fluid is admitted to the cylinders 94 through the conduits 186, the fluid in the conduits 188 also being subjected to pressure to hold the check valves 190 closed. The first effect of the fluid admitted to the cylinders 94, acting through the pistons 92 on the toggles 72, 74 of the stapling units, is to advance the outside formers 44 and their cutters 68 far enough to engage the cutters lightly with the staple-forming wire extending downwardly into the units, downward swinging movements of the units about the axes of the shafts 18 being yieldingly resisted by the springs 148. These springs are, however, weak enough to permit the units thereafter to be swung downwardly by further movements of the pistons 92 while further operative movements of the outside formers and the cutters are prevented by the resistance of the wire, the cutters therefore acting to feed portions of the wire downwardly past the brake members 176 which thereafter prevent reverse movement of the wire. In this manner the anvils 102 of the stapling units are carried downwardly into engagement with the insole in locations farther inwardly than its lip to position the units in proper relation to the shoe. By reason of the resistance of the shoe to further downward movements of the units the toggles 72, 74 are then further straightened to cut the wire, to operate the outside formers to form staples over the inside formers, and to move the throats 38 inwardly into engagement with the upper in the angle between the feather and the lip of the insole (Fig. 9) in locations between the forward ends of the wipers and the binder-holding grippers 10. At the same time the bars 12 of the units are moved in outward directions by the levers 108 to cause the anvils 102 to engage the inner face of the lip of the insole, so that the lip and the margin of

the upper are clamped between the throats and the anvils. To insure that the portions of the binder engaged by the staples will be positioned in proper relation to the staple-guiding passageways in the throats, the fingers 124 are moved inwardly and upwardly to engage the binder underneath and to raise it to the proper height. After the throats have completed their inward movements, further straightening of the toggles

10 72, 74 serves to move the blocks 82 outwardly against the resistance of the springs 84, so that these blocks assume positions determined by the positions of the throats, the straightening of the toggles being positively limited by the stop members 122.

As the stapling units are swung downwardly in the manner above described, the driver-operating pistons 142 are pulled downwardly by the units to uncover the ports 150, and these ports 20 also are uncovered by the pistons 92 in the downward movements of these pistons. This serves to admit operating fluid from the cylinders 94 to the cylinders 144. Operative movements of the staple drivers are, however, prevented by the 25 stop members 154 until these members are displaced by the toggle links 72 (Fig. 9) near the end of the operative movements of the throat-operating toggles, whereupon the drivers are operated by the toggles 130, 132. The staples are 30 thus driven through the margin of the upper and the lip of the insole and their legs are clinched in directions toward the heel end of the shoe by the anvils 102 (Fig. 12). The straightening of the driver-operating toggles is limited by the stop members 122. Since the links 132 of the driver-operating toggles are connected to the blocks 82 which, as above described, are moved to positions determined by the positions of the throats 35 38 when the latter are in engagement with the upper, the driver-operating toggles are adjusted by the blocks so that the limits of the operative movements of the drivers are determined in accordance with the positions of the throats. Insurance is thus afforded that when the drivers 40 are at the limits of their staple-driving movements their end faces will be in a definitely pre-determined relation to the ends of the staple-guiding passageways in the throats, which relation may be varied by turning the eccentric studs 45 80 (Fig. 7).

Before the staple drivers complete their operative movements the grippers 10 are opened to release the binder in the manner disclosed in application Serial No. 568,964. After the driving 55 of the staples the fluid is released automatically from the cylinders 94 and 144 by the valve mechanism also fully disclosed in that application. The springs 100 and 148 then act to return the parts of the stapling units to their initial positions relatively to one another and, as soon as the cutters 60 68 are retracted beyond the lower ends of the strands of staple-forming wire, to impart also to the stapling units their upward swinging movements about the axes of the shafts 18. The units 65 thus move upwardly along the strands of wire, which are held against upward movement by the brake members 176, and they thereby receive the wire for use in forming the next staples, the upward movement of each unit being limited by its engagement with the end of the wire. Near the end of the upward movements of the units the clutch is automatically actuated to cause the machine to resume and complete its cycle of operations, as further disclosed in application Serial 70 75 No. 568,964.

Having described the invention, what I claim as new and desire to secure by Letters Patent of the United States is:

1. In a shoe machine, the combination with means for positioning a shoe having an insole provided with a lip arranged to be engaged by the margin of the lasted upper, of mechanism for inserting a fastening in the margin of the upper and the lip of the insole in a direction widthwise of the lip, and power-operated means for moving said mechanism heightwise of the shoe in a direction transverse to the direction of fastening insertion to bring it into positioning engagement with the shoe and for thereafter operating it first to press the upper against the lip and then to insert the fastening.

2. In a shoe machine, the combination with means for positioning a shoe having an insole provided with a lip arranged to be engaged by the margin of the lasted upper, of mechanism for driving a fastening through the margin of the upper and the lip of the insole in a direction widthwise of the lip, said mechanism including an anvil arranged to engage the inner face of the lip and to clinch the fastening, and means for moving said mechanism heightwise of the shoe to a position determined by engagement of said anvil with the insole and for thereafter operating it to drive the fastening.

3. In a shoe machine, the combination with means for positioning a shoe having an insole provided with a lip arranged to be engaged by the margin of the lasted upper, of mechanism for driving a fastening into the margin of the upper and the lip of the insole in a direction widthwise of the lip, said mechanism including a throat member for guiding the fastening and a driver for driving it, the throat member and the driver being movable as a unit heightwise of the shoe in a direction transverse to the direction of the drive to a position determined by engagement of the mechanism with the insole prior to the driving of the fastening.

4. In a shoe machine, the combination with means for positioning a shoe having an insole provided with a lip arranged to be engaged by the margin of the lasted upper, of mechanism for driving a fastening through the margin of the upper and the lip of the insole in a direction widthwise of the lip, said mechanism being mounted for movement heightwise of the shoe to a position determined by the shoe and including a throat member and a clinching anvil relatively movable thereafter to clamp the margin of the upper and the lip between them prior to the driving of the fastening.

5. In a shoe machine, the combination with means for positioning a shoe having an insole provided with a lip arranged to be engaged by the margin of the lasted upper, of mechanism for driving a fastening through the margin of the upper and the lip of the insole in a direction widthwise of the lip, said mechanism including an anvil arranged to engage the inner face of the lip and to clinch the fastening and a throat member for guiding the fastening, and means for moving the mechanism heightwise of the shoe to a position determined by engagement of said anvil with the insole and for thereafter moving the anvil and the throat member toward each other to clamp the margin of the upper and the lip between them prior to the driving of the fastening.

6. In a shoe machine, the combination with means for positioning a shoe having an insole

provided with a lip arranged to be engaged by the margin of the lasted upper, of mechanism for forming a staple and for driving it into the margin of the upper and the lip of the insole in a direction widthwise of the lip, and means for moving said mechanism heightwise of the shoe in a direction transverse to the direction of the drive to position it relatively to the shoe and for then operating it to form and to drive the staple.

10. 7. In a shoe machine, the combination with means for positioning a shoe having an insole provided with a lip arranged to be engaged by the margin of the lasted upper, of mechanism for forming a staple and for driving it into the margin of the upper and the lip of the insole in a direction widthwise of the lip, and means for moving said mechanism heightwise of the shoe to a position determined by its engagement with the shoe and for then operating it to form a staple in response to resistance of the shoe to its further movement heightwise thereof.

8. In a shoe machine, the combination with means for positioning a shoe having an insole provided with a lip arranged to be engaged by the margin of the lasted upper, of mechanism for forming a staple and for driving it into the margin of the upper and the lip of the insole in a direction widthwise of the lip, said mechanism being mounted for movement heightwise of the shoe to a position determined by the shoe and including a staple-forming member and a toggle for operating it, and means arranged to act through said toggle first to move the mechanism heightwise of the shoe and then to operate its staple-forming member in response to resistance of the shoe to its further movement heightwise thereof.

9. In a shoe machine, the combination with means for positioning a shoe having an insole provided with a lip arranged to be engaged by the margin of the lasted upper, of mechanism for forming a staple and for driving it into the margin of the upper and the lip of the insole in a direction widthwise of the lip, said mechanism being mounted for movement heightwise of the shoe to a position determined by engagement with the shoe and including a staple-forming member and a toggle for operating it, the staple-forming member having a cutter movable therewith to cut from wire a piece to form a staple, and means arranged to act through said toggle first to move the mechanism heightwise of the shoe by reason of resistance of the wire to movement of the staple-forming member and cutter and then to operate said cutter and member to cut the wire and to form a staple by reason of resistance of the shoe to further movement of the mechanism heightwise thereof.

10. In a shoe machine, the combination with means for positioning a shoe having an insole provided with a lip arranged to be engaged by the margin of the lasted upper, of mechanism for forming a staple and for driving it into the margin of the upper and the lip of the insole in a direction widthwise of the lip, said mechanism being movable heightwise of the shoe to position it relatively to the shoe and including a staple-forming member movable thereafter to form a staple, and means for supplying wire to said mechanism from which to form the staple, said mechanism having means for feeding the wire by its positioning movement heightwise of the shoe.

11. In a shoe machine, the combination with means for positioning a shoe having an insole

provided with a lip arranged to be engaged by the margin of the lasted upper, of mechanism for forming a staple and for driving it into the margin of the upper and the lip of the insole in a direction widthwise of the lip, said mechanism being movable heightwise of the shoe to position it relatively to the shoe and including a staple-forming member movable thereafter to form a staple and a cutter movable with said member for cutting from wire a piece of the proper length for the staple, and means for supplying wire to said mechanism, the cutter being arranged to engage the wire and to feed it in response to the positioning movement of the mechanism heightwise of the shoe.

12. In a shoe machine, the combination with means for positioning a shoe having an insole provided with a lip arranged to be engaged by the margin of the lasted upper, of mechanism for forming a staple and for driving it into the margin of the upper and the lip of the insole in a direction widthwise of the lip, said mechanism being mounted for movement heightwise of the shoe to a position determined by the shoe and including a staple-forming member movable thereafter to form a staple and a cutter movable with said member to cut from wire a piece of the proper length for the staple, the mechanism further including a toggle for operating its staple-forming member and cutter, means for supplying wire to said mechanism, and means arranged to act through said toggle to engage the cutter with the wire and to feed the wire by the movement of the mechanism heightwise of the shoe and thereafter to operate the cutter and the staple-forming member to cut the wire and to form the staple.

13. In a shoe machine, the combination with means for positioning a shoe having an insole provided with a lip arranged to be engaged by the margin of the lasted upper, of mechanism for forming a staple and for driving it into the margin of the upper and the lip of the insole in a direction widthwise of the lip, said mechanism being mounted for movement heightwise of the shoe to position it relatively to the shoe and for return movement to starting position after the driving of the staple, and means for conducting wire to said mechanism from which to form the staple, the mechanism having means for feeding the wire by its positioning movement heightwise of the shoe and being movable relatively to the wire to receive a length of wire for the next staple in its return to starting position.

14. In a shoe machine, the combination with means for positioning a shoe having an insole provided with a lip arranged to be engaged by the margin of the lasted upper, of mechanism for forming a staple and for driving it into the margin of the upper and the lip of the insole in a direction widthwise of the lip, said mechanism being mounted for movement heightwise of the shoe to position it relatively to the shoe prior to the forming and driving of the staple, and means for conducting wire to the mechanism from which to form the staple, the mechanism having means for feeding the wire by its positioning movement heightwise of the shoe and being reversely movable relatively to the wire to a position determined by its engagement with the end of the wire after the staple-driving operation.

15. In a fastening-inserting machine, the combination with work-positioning means, of mechanism for forming a staple and for driving it into the work, said mechanism being mounted for

movement in a direction transverse to the direction of the drive to position it relatively to the work and including a member movable to form a staple, and means for supplying wire to said mechanism from which to form the staple, said mechanism having means for feeding the wire by its movement to position it relatively to the work.

16. In a fastening-inserting machine, the combination with work-positioning means, of mechanism for forming a staple and for driving it into the work, said mechanism being mounted for movement in a direction transverse to the direction of the drive to position it relatively to the work and including a member movable to form a staple and a cutter movable with said member for cutting from wire a piece of the proper length for the staple, and means for supplying wire to said mechanism, the cutter being arranged to engage the wire and to feed it in response to the movement of the mechanism to position it relatively to the work.

17. In a fastening-inserting machine, the combination with work-positioning means, of mechanism for forming a staple and for driving it into the work, said mechanism being mounted for movement in a direction transverse to the direction of the drive to position it relatively to the work and including a member movable to form a staple and a cutter movable with said member to cut from wire a piece of the proper length for the staple, the mechanism further including a toggle for operating its staple-forming member and cutter, means for supplying wire to said mechanism, and means arranged to act through said toggle to engage the cutter with the wire and to feed the wire by imparting the positioning movement to the mechanism and thereafter to operate the cutter and the staple-forming member to cut the wire and to form the staple.

18. In a fastening-inserting machine, the combination with work-positioning means, of mechanism for forming a staple and for driving it into the work, said mechanism being mounted for movement in a direction transverse to the direction of the drive to position it relatively to the work and for return movement to starting position after the driving of the staple, and means for conducting wire to said mechanism from which to form the staple, the mechanism having means for feeding the wire by its movement to position it relatively to the work and being movable relatively to the wire to receive a length of wire for the next staple in its return to starting position.

19. In a fastening-inserting machine, the combination with work-positioning means, of mechanism for forming a staple and for driving it into the work, said mechanism being mounted for movement in a direction transverse to the direction of the drive to position it relatively to the work, means for conducting wire to the mechanism from which to form the staple, the mechanism having means for feeding the wire by its movement to position it relatively to the work and being reversely movable relatively to the wire to a position determined by its engagement with the end of the wire after the staple-driving operation, and means for holding the wire against reverse movement to render it effective thus to determine the position of the mechanism.

20. In a fastening-inserting machine, the combination with work-positioning means, of mechanism for driving a fastening into the work, said mechanism including a throat member movable into engagement with the work for guiding the fastening, a driver for driving the fastening, tog-

15

gles associated respectively with said throat member and driver for operating them, and means for operating said toggles by forces applied at the knees of the toggles.

21. In a fastening-inserting machine, the combination with work-positioning means, of mechanism for forming a staple and for driving it into the work, said mechanism including a member movable to form a staple and a driver for driving the staple, toggles associated respectively with said staple-forming member and driver for operating them, and means for operating said toggles by forces applied at the knees of the toggles.

22. In a fastening-inserting machine, the combination with work-positioning means, of a driver for driving a fastening into the work, a throat member movable to a position determined by its engagement with the work for guiding the fastening, a toggle for thus moving said throat member, another toggle for operating the driver, and means for controlling said driver-operating toggle by said first-named toggle to limit the operative movement of the driver in accordance with the position of the throat member.

23. In a fastening-inserting machine, the combination with work-positioning means, of a driver for driving a fastening into the work, a throat member movable to a position determined by its engagement with the work for guiding the fastening, a toggle for thus moving said throat member, another toggle for operating the driver, and a connection between said toggles movable by said first-named toggle to adjust the driver-operating toggle in accordance with the position of said throat member in engagement with the work and thereby to determine the limit of the operative movement of the driver in accordance with the position of the throat member.

24. In a fastening-inserting machine, the combination with work-positioning means, of a driv-

er for driving a fastening into the work, a throat member movable to a position determined by its engagement with the work for guiding the fastening, a toggle for thus moving said throat member, said toggle being further movable to a predetermined limit after the engagement of the throat member with the work, another toggle for operating the driver also movable to a predetermined limit, and means for adjusting the driver-operating toggle by such further movement of the first-named toggle to determine the limit of the operative movement of the driver in accordance with the position of the throat member.

25. In a fastening-inserting machine, the combination with work-positioning means, of a driver for driving a fastening into the work, a throat member movable to a position determined by its engagement with the work for guiding the fastening, a toggle for thus moving said throat member, another member movable by one of the links of said toggle a distance determined by the position of said throat member after it has engaged the work, and another toggle for operating the driver, one of the links of said driver-operating toggle being connected to said other member for adjusting that toggle by the movement of said other member to determine the limit of the operative movement of the driver in accordance with the position of the throat member.
